US00D587914S

(12) **United States Design Patent**
Weber et al.

(10) **Patent No.:** **US D587,914 S**
(45) **Date of Patent:** **** Mar. 10, 2009**

(54) **CHAIR**

(75) Inventors: **Jeffrey A. Weber**, Minneapolis, MN (US); **Douglas M. VanDeRiet**, Holland, MI (US)

(73) Assignee: **Herman Miller, Inc.**, Zeeland, MI (US)

(**) Term: **14 Years**

(21) Appl. No.: **29/294,868**

(22) Filed: **Jan. 28, 2008**

(51) LOC (9) Cl. **06-01**

(52) U.S. Cl. **D6/364**

(58) Field of Classification Search D6/500-502, D6/366, 340, 349, 364, 334-335, 356, 365, D6/367, 368, 374; 297/202, 214, 452.12, 297/452.26, 452.27, 452.28, 452.29, 452.32, 297/452.37, 452.21, 411.2

See application file for complete search history.

(57) **CLAIM**

The ornamental design for a chair, as shown and described.

DESCRIPTION

FIG. 1 is a perspective view of a chair showing our new design;

FIG. 2 is a front view of the chair shown in FIG. 1;

FIG. 3 is a rear view of the chair shown in FIG. 1;

FIG. 4 is a right side view of the chair shown in FIG. 1;

FIG. 5 is a left side view of the chair shown in FIG. 1;

FIG. 6 is a top view of the chair shown in FIG. 1; and,

FIG. 7 is a bottom view of the chair shown in FIG. 1.

The broken lines showing armrests, a base and/or controls in the Figures are for environmental purposes only and do not form any part of the claimed design.

1 Claim, 7 Drawing Sheets
